UNITED STATES PATENT OFFICE.

GEORGE W. GRAVES, OF AMARILLO, TEXAS.

DESIGN FOR A BRIDLE-BIT.

SPECIFICATION forming part of Design No. 34,573, dated May 28, 1901.

Application filed April 25, 1901. Serial No. 57,505. Term of patent 7 years.

To all whom it may concern:

Be it known that I, GEORGE W. GRAVES, a citizen of the United States, residing at Amarillo, in the county of Potter and State of Texas, have invented and produced a new and original Design for a Bridle-Bit; and I do hereby declare the following to be a full, clear, and exact description of the invention, such as will enable others skilled in the art to 5 which it appertains to make and use the same, reference being had to the accompanying drawings, and to letters of reference marked thereon, which form a part of this specification.

10 Figure 1 is a perspective view of my newly-designed bit for horses, &c., and Fig. 2 is a side elevation of the same.

15 In said drawings, *a* indicates the mouth part, and *b b* are the cheek parts.

As shown in the accompanying drawings, 20 the leading or material feature of my design consists of the peculiarly-shaped cheek parts, which are shaped in resemblance to a man on horseback.

d is the horse-shaped part, and *c* is the part 25 shaped in resemblance to a man on the back of said horse.

What I claim as new is—

The design for a bit, substantially as shown and described.

In testimony that I claim the foregoing I have hereunto set my hand this 22d day of March, 1901.

GEORGE W. GRAVES.

Witnesses:

HARRY W. BROWN,
WILLIAM H. DRAKE.
